HEATING SYSTEM *

Horace S. Kehm, Chicago, Ill.

Application October 13, 1933, Serial No. 693,429

2 Claims. (CL. 237—19)

This invention relates in general to a heating system and is particularly concerned with improvements in heating systems of the type wherein the circulation of hot water is utilized to transfer the heat energy from a boiler to remotely located radiating means.

It is a primary object of the present invention to provide a combined house and domestic hot water heating system which may be utilized for simultaneously furnishing heat and domestic hot water, and is so arranged that the system may be easily and quickly adapted to economically and efficiently furnish domestic hot water only.

It is a further object of the invention to provide a heating system wherein the entire supply of hot water from the boiler passes through a domestic hot water heating device and is automatically diverted into parallel paths and returned to the boiler, one of these paths being provided with valve means operable to obstruct the flow in its associated path, whereby the entire flow from the boiler may be caused to pass through the hot water heating device and return to the boiler through the other of the parallel paths.

It is a further object of the herein described invention to provide in a heating system having a domestic hot water heater of the indirect type so connected as to utilize hot water from the boiler, means whereby the hot water after passing through the heater may be forcibly circulated upon demand through a remote heat radiating device and returned to the boiler without interfering with the functioning of the domestic hot water heating device.

It is also an object of this invention to provide in a combined house and domestic hot water heating system, means whereby hot water from a boiler may be caused to flow by gravity through the hot water heating portion of the system and may be forcibly circulated upon demand through the house heating portion of the system.

Still another object resides in the provision of an improved heating system which is economical to install, which is devoid of check valves, motor operated valves and the like, which is efficient in operation, and wherein the hot water from the boiler is positively circulated through the radiators, thereby enabling the radiators to be placed below the boiler, if desired.

In accordance with the general features of the present system, it is proposed to provide a single pipe main in the form of a loop to which the radiators are connected by supply and return risers respectively. Moreover, the feed from the boiler

to the main is carried through a domestic hot water heater of the indirect type, and the ends of the main loop are shunted by a conduit. It will be observed that with such a system the main at each radiator also constitutes a shunt or bypass for the radiators. A pump is disposed outside the local circuit of the domestic hot water heater through the shunt conduit, this pump being actuatable upon demand to forcibly circulate hot water through the radiator loop main. It will be noted that if the supply and return risers of the radiators and the shunt conduit between the ends of the looped main were connected in T-fittings in the usual manner, there would be very little hot water circulated through the radiators and this shunt due to its velocity past the risers and shunt connections. To overcome this difficulty means are provided at the end connections of the shunt and the ends of the risers which are connected to the main for automatically deflecting a portion of the flow of hot water through the radiators and through the conduit shunt as will be more fully explained in the following description.

Other objects and features of this invention will more fully appear from the following detailed description taken in connection with the accompanying drawing which illustrates a single embodiment thereof, and in which

Figure 1 is a diagrammatic view of a single pipe hot water heating system embodying the features of this invention.

Figure 2 is an enlarged fragmentary sectional detailed view illustrating the joint connection between one end of a shunting conduit and the boiler outlet connection to the heating system main, taken substantially on line II—II of Figure 1; and

Figure 3 is a similar view illustrating the joint connection between the other end of the shunting conduit and the inlet connection to the boiler from the heating system main, taken substantially on line III—III of Figure 1.

As shown on the drawing:

In the illustrated embodiment of the present invention there is shown in Figure 1 a boiler 10 which is connected at its outlet to one end of a single pipe main 11 which is formed into a loop and is connected at its other end to the inlet 12 of the boiler. Although a plurality of radiators such as shown at 13 may be connected to the main 11, it is not thought necessary to illustrate each radiator and for this reason only one is shown as being connected to the main. The

radiators are each connected to the main through a supply riser 13 and a return riser 14.

At the boiler there is provided in the outlet connection of the main from the boiler a domestic hot water heating device generally indicated at 15 and comprising a tank 16 having an inlet connection 17 for cold water and an outlet connection 18 by means of which the heated water may be carried to any desired fixture. Inside the tank the fluid flowing from the boiler passes through a heating coil 19, whereby the water within the tank for the domestic hot water supply is indirectly heated.

Adjacent the outlet side of the hot water heating device, the main 11 is connected to one end of a conduit 20 having its other end connected into the boiler inlet connection of the main, the conduit 20 thereby forming a bypass or shunt connection between the ends of the looped main 11, which is outside the hot water heating device 15.

In order to prevent the circulation of hot water through the main 11 by gravity, a trap 21 is provided at the supply end of the main 11 adjacent its connection to the shunting conduit 20. This trap is of a smaller section of pipe than the main so as to form a contracted passageway for normally retarding the flow of hot water into the house heating portion of the system. Valves 22 and 23 are respectively provided in the supply and return connections of the main to the boiler so that the house heating portion of the system may be rendered ineffective by the closure of these valves, when it is not desired 35 to use the house heating portion of the system.

It will be observed that gravity flow is not depended upon for circulating the hot water through the house heating portion of the system and for this purpose, a pump 24 is provided 40 in the return connection of the main 11 to the boiler. While this pump may be driven by any appropriate power means, it is preferred to drive the pump through the agency of an electric motor which is energized from suitable power source 45 through conductors 25 and 26. A thermostatically actuated switch 27 is provided with contacts to control the operation of the motor in response to changes of temperature at the point where the thermostatic switch may be located. It is preferable to mount this switch at a point where the average room temperature will be that which is desired to be maintained.

For controlling the temperature of heated water from the boiler, a suitable aquastat 28 is provided at the outlet connection of the main to the boiler. This aquastat may be of any appropriate design or construction and is provided with contacts for opening and closing an electrical circuit 29 which may form a part of the 55 control system of a gas valve, oil burner motor or other means for firing the boiler.

An expansion tank 30, of the ordinary type is connected through a pipe 31 to the connection of the main 11 to the outlet of the boiler. As 60 in the ordinary heating system, the expansion tank should be placed at a height above the elevation of the highest radiator of the system.

Since the heated boiler water is forcibly circulated by means of the pump 24, it is impracticable to use ordinary T-connections for the shunt conduit 20 and for the connection of the supply and return risers of the radiators to the main. The joint generally indicated at 32 will 65 be more clearly understood by reference to Figure 2.

In this case a T-shaped fitting 33 of conventional type is provided having aligned threaded openings 34 and 35 and a lateral branch opening 36 which would be connected to a shunt conduit 20 or, if this fitting is installed in connection with the radiators, to the riser supply connection 13 at each radiator. Inlet to the T is through the main 11 which is threaded into the opening 35. In the opening 34 there is threadedly inserted a plug 37 having an eccentrically disposed bore 38 which terminates in a prolonged tubular extension 39 which projects past the lateral branch connection of the T. It will be observed that the axis of the bore of the plug 37 is disposed below the axis of the main 11 and 10 that the outer end of this plug is threaded to receive a section of the main 11. With this arrangement, water approaching from the left as indicated by the arrow in Figure 2 passes into the T and meets the obstruction formed by the 20 plug with the result that the water readily flows out the branch connection to the T. The bore of the plug 37 is smaller than that of the main and permits a portion only of the water to pass directly on into the continuation of the main 11. 25

At a joint 40 or in the case of the return riser 14 connection to the main 11, the joint is as shown in Figure 3. This joint is in general the same as shown in Figure 2 except that instead of the fluid entering directly into the T 30 through the main 11, it first flows through the bore of the plug 37. Moreover, in this case, instead of the axis of the bore and tubular extension being disposed below the axis of the main 11, the axis of the bore and tubular extension 35 are disposed above the axis of the main 11. With water flowing from the tubular extension 39 from the left as indicated by the arrow, there will be little or no tendency for water to pass upwardly in the branch connection 20. The 40 tubular extension will direct the water flowing therethrough, which will be hotter than that returning through the branch conduit 20, along the upper portion of the main for permitting the cooler water from the branch connection to 45 follow its natural tendency to descend to the bottom of the main with less than normal resistance. Since the tubular extension 39 is disposed towards the upper portion of the main 11, any flow of water in the reverse direction will 50 tend to be retarded from flowing in the opposite direction through the branch connection by virtue of the obstruction afforded by the plug and tubular extension.

The operation of the system of my invention 55 will now be described:

Assuming that it is desired to simultaneously heat the radiators and provide domestic hot water, the valves 22 and 23 should be in open position. The aquastat 28 will be set at a pre- 60 determined temperature of, for example, 130° to 180°, depending on the need for domestic hot water. This aquastat will control the boiler to give uniformly heated boiler water which circulates by gravity through the coil 19 of the hot 65 water heater 15. Upon emerging, the water is substantially all deflected at joint 32 through the conduit 20 and thence thru joint 40 back into the boiler. The choke or trap 21 operates in conjunction with joint 32 to retard circulation of 70 the hot water in the house heating portion of the system until such time as there is a call for heat therein. It will be observed that in the above described operation of this portion of the system, boiler water is confined to the boiler 75

and domestic hot water heater until the thermostat 27 calls for heat.

As soon as the room thermostat operates, its contacts are closed and the pump 24 is energized to force hot water to all radiators at once and back into the boiler through joint 40 which prevents back-up of water into the conduit 20. Thus an abundant supply of domestic hot water and an absolutely uniform temperature are obtained at all times with great savings in fuel cost.

The mild heat which is an advantage of hot water heat is not lost as hot water from the boiler is slightly cooled in the domestic hot water heater to proper home heating temperature before being forced to the radiators.

When it is desired, for example in the summer time, to have domestic hot water without the necessity of operating the house heating portion 20 of the system, the valves 22 and 23 are closed. By this simple operation, the circulation of boiler hot water is confined to the boiler and domestic hot water heater, the entire flow passing through conduit 20 and being circulated by gravity. As in the previous case the temperature of the water is automatically controlled through the aquastat 28.

From the foregoing description it will be apparent that the present invention provides an improved heating system which may be utilized to simultaneously furnish domestic hot water and heat to the radiators and is so arranged that it may be quickly adapted to furnish domestic hot water only; a system which is economical to install, which is devoid of check valves, motor operated valves and the like, which is efficient in operation, and wherein the hot water is positively circulated from the boiler to the radiators so that the radiators and boiler 40 will operate at their greatest efficiency.

Now, it is of course, to be understood that al-

though I have described in detail the preferred embodiment of my invention, the invention is not to be thus limited but only insofar as defined by the scope and spirit of the appended claims.

I claim as my invention:

1. A hot water heating system comprising a boiler, a domestic water heater connected to said boiler by a first pipe loop comprising a first feed and a first return pipe, a hot water radiator 10 connected shunting a portion of said first return pipe by a second pipe loop comprising a second feed and a second return pipe, a water trap in said second feed pipe adjacent its point of connection with said first return pipe and disposed 15 to provide a water column below said point of connection, a pump for intermittent duty in said second return pipe, and stationary flow restricting and directing means in said second feed pipe at its connection with said first return pipe and 20 also in said second return pipe at its connection with said first return pipe.

2. A hot water heating system comprising a boiler, a domestic water heater connected to said boiler by a first pipe loop comprising a first feed 25 and a first return pipe, a hot water radiator connected shunting a portion of said first return pipe by a second pipe loop comprising a second feed and a second return pipe, a water trap in said second pipe loop including a conduit having 30 a predetermined smaller bore than that of the main run of pipe in the loop so as to form a contracted passageway for normally retarding the flow of hot water to the radiator, a pump for intermittent duty in said second return pipe, and 35 stationary flow restricting and directing means in said second feed pipe at its connection with said first return pipe and also in said second return pipe at its connection with said first return pipe.

HORACE S. KEHM.
